UNITED STATES PATENT OFFICE.

MADGE CHRISTINE MORRIS, OF CATFORD, LONDON, ENGLAND.

DESIGN FOR A COVER FOR DRIVERS OF MOTOR-CARS, MOTOR-BUSES, OR THE LIKE VEHICLES.

47,306.

Specification for Design.

Patented May 4, 1915.

Application filed October 16, 1912. Serial No. 726,127. Term of patent 3½ years.

To all whom it may concern:

Be it known that I, MADGE CHRISTINE MORRIS, a subject of the King of Great Britain and Ireland, residing at 24 Minard road, Catford, London, England, have invented a new, original, and ornamental Design for a Cover for the Drivers of Motor-Cars, Motor-Buses, or the like Vehicles, of which the following is a specification, reference being had to the accompanying drawing, forming part thereof.

Figure 1 is a front view and Fig. 2 a rear view of a cover for the drivers of motor

cars, motor busses or the like vehicles embodying my invention, which cover is designed for the use of drivers of motor vehicles who are completely exposed to the weather.

I claim:—

The ornamental design for a cover for the drivers of motor cars, motor busses, or the like vehicles as shown and described.

MADGE CHRISTINE MORRIS.
